BOREHOLE SAMPLER

James S. Crump, Houston, Tex., assignor to
Standard Oil Development Company, a corpora-
tion of Delaware

Application August 29, 1940, Serial No. 354,658

7 Claims. (CL 166—19)

The present invention is directed to a device adapted to be carried on a wire line for procuring a sample of borehole fluid under pressure and bringing said sample to the surface without any release in pressure.

The principal object of the present invention is the provision of a device of the character described having a sample chamber provided with an inlet port, normally sealed by a disc, and means for rupturing the disc at any desired depth in the borehole.

An additional object of the present invention is the provision of a device of the character described in which the disc rupturing means is operated by an upward jerk on the wire line on which the entire device is carried.

Further objects and advantages of the present invention will appear from the following detailed description of the accompanying drawing in which—

Figure 1 is the upper half of a device according to the present invention in vertical section; Figure 2 is a corresponding view of the lower half of the device; and

Figure 3 is a section along the line C—C of Figure 2.

Referring to the drawing in detail, numeral 1 designates a cylindrical cap in the upper end of which is nested an anchor 2 in which is embedded a wire line 3 which passes through the cap and serves to suspend the assembly as a whole in the borehole. The interior of the lower end of the cap is threaded to receive a plug 4 having a nipple 5 threaded interiorly and exteriorly, an exteriorly threaded end 6, and a central longitudinal passage 7 communicating with a radial passage 8 which is sealed off by a threaded plug 9. Threaded into the interior of the nipple 5 is a sleeve 10 having interior and exterior threads, and being adapted to be forced down upon packing material 11. Threaded into the sleeve is a screw 12 carrying a needle valve 13 adapted to seal off passage 7.

Carried by the threaded end 6 is a cylinder 14 which constitutes the sample holding chamber. It is to be understood that this cylinder can be made any desired length and is made of steel of sufficient strength to withstand pressures encountered in the borehole.

Carried by the lower end of cylinder 14 is a bushing 15. This bushing has three distinct parts, one of which is the plug 16 which screws into the lower end of cylinder 14 and is of such wall thickness as to present an annular surface to the interior of the cylinder, and has a central

longitudinal passage 17, communicating with a larger central passage 18 in the main portion of the bushing, which in turn communicates with a still larger central passage defined by the skirt portion 19 of the bushing. Portion 16 also has a longitudinal passage 20 arranged in its annular wall connecting passage 18 with the interior of cylinder 14.

The skirt portion 19 of the bushing carries a nipple 21 on the inner end of which is arranged a gasket 22 adapted to be pressed against the annular shoulder formed between passage 18 and the skirt portion, and to form a seat for the knife edge 23 of a check valve 24 which is carried by a stem 25 slidably mounted in a circular plate 26 in cylinder 14. The check valve is normally pressed against its seat by a spring 27.

Nipple 21 has a central passage in which is provided a shoulder 28 on which is arranged a metal disc, preferably made of steel, 29, which is held in place by a bolt 30 having a central passage 31 in alignment with the central passage of the nipple 21. The lower end of nipple 21 carries a nose plug 32 which has a central passage 33 in communication with the central passage 31.

Screwed into the lower face of the check valve 24 is a spear 34 which is of such length that it penetrates disc 29 when the check valve 24 is on its seat. The disc 29 is of such strength that the spear 34 normally rests upon it and holds the check valve 24 on its seat against the action of spring 27. The spear is caused to penetrate the disc by an impact on the stem of the check valve.

The stem 25 of the check valve extends above the circular plate 26. Screwed into the annular portion of element 16 are three spaced rods 35 extending upwardly through the plate 26 and terminating near the upper end of cylinder 14. The upper ends of these rods 35 are held in spaced relation by a second circular plate 36 which has a central opening 37 across which is arranged a bolt 38 on which is anchored one end of a spring 39. The other end of the spring is anchored to a similar bolt 40 fixed in the longitudinal recess 41 of a cylindrical weight member 42 which is slidably arranged on the bars 35, which serve as guide rods. It will be apparent that if the entire assembly is given an upward jerk the inertia of the weight member 42 causes it to deliver an impact to the stem 25 which serves to rupture the disc 29.

In the drawing the spear is shown protruding through the disc. It will be understood, however, that when the device is lowered into the borehole the point will rest on top of the disc

with the needle valve 13 in closed position. When the sampling point is reached, the wire line is given an upward jerk and then the device is permitted to rest until a sample is collected. It will be understood that when the 5 disc 29 is ruptured the pressure of the formation fluid will force the check valve 24 off its seat and the fluid will pass through passage 20 into the interior of the cylinder until the pressure inside this cylinder 14 becomes equal to the external pressure when the spring 27 will force the check valve back onto its seat. In order that liquid may pass through the disc it is desirable to make the spear of such configuration that it will not completely fill the hole which it punctures in the disc. For example, the stabbing point may be conical with longitudinal 10 grooves, or it may have longitudinal ribs arranged on it. After the sample is collected and the valve 24 is back on its seat, the device is withdrawn from the borehole, the cap is removed, needle valve 13 is opened, and the liquid sample drawn through passage 8 by first removing plug 9. It is usually advisable to remove the plug 9 and connect the device to a collection vessel 15 before opening the needle valve.

The above described embodiment is not to be taken as the only possible embodiment of the present invention. It will be apparent that this particular embodiment is an illustration of one form of the present invention which is capable of assuming different forms by the substitution of equivalent elements for some of the elements described. Various forms of rupturing devices and devices for delivering an impact to the rupturing device will occur to those skilled in the art and are contemplated within the scope of the present invention.

The nature and objects of the present invention having been thus described and illustrated, 40 what is claimed as new and useful and is desired to be secured by Letters Patent is:

1. A device adapted to be carried by a wire line for collecting a liquid sample in a borehole at any desired point therein comprising a chamber, means for sealing off said chamber including a disc, and means for rupturing said disc at any desired point operable by an upward jerk on the line carrying said device while said device is freely suspended by said wire line in said 45 bore hole.

2. A device adapted to be carried by a wire line for collecting a liquid sample at any desired point in a borehole comprising a chamber, means

for sealing the lower end of said chamber comprising a disc, a spear arranged within said chamber in position to puncture said disc, and means for delivering an impact to said spear upon the application of a jar to the device while said device is freely suspended by said wire line in said bore hole.

3. A device adapted to be carried by a wire line for collecting a liquid sample at any desired point in a borehole comprising a chamber, a valve at the upper end of said chamber, means for sealing the lower end of said chamber comprising a disc, a spear arranged in said chamber in position to puncture said disc and means for delivering an impact to said spear upon the application of a jar to the device while said device is freely suspended by said wire line in said bore hole.

4. A device adapted to be carried by a wire line for collecting a liquid sample at any desired point in a borehole comprising a chamber, means for sealing the lower end of said chamber comprising a disc, a spear arranged in said chamber in position to puncture said disc, a weight suspended within said chamber above said spear and means for causing said weight to impinge upon said spear upon the application of a jar to the device.

5. A device according to claim 4 in which the weight is slidably arranged on guide rods fixed in the chamber and is suspended by a spring.

6. A device adapted to be carried by a wire line for collecting a liquid sample at any desired point in a borehole comprising a chamber, means for sealing the lower end of said chamber comprising a check valve normally pressed on its seat by a spring, a passage extending from said chamber to the exterior of the device and controlled by said check valve, a disc arranged across said passage below said check valve, a spear carried by said check valve and adapted to rest on said disc and hold said check valve off its seat, and means for delivering an impact to said spear upon the application of a jar to said device whereby the disc is ruptured by the spear.

7. A device according to claim 6 in which the check valve is carried on a slideable stem and the means for delivering an impact to the spear is a weight arranged in the chamber in spaced relation to said stem and adapted to be thrust against the end of said stem upon the application of a jar to the device.
